SWIM BOARD

Roger A. Del Mar, Los Angeles, Calif., assignor to Aeroplastics Corporation, Venice, Calif., a corporation of California

Filed Nov. 21, 1960, Ser. No. 62,917

Term of patent 14 years

(Cl. D71—1)

FIGURE 1 is a top plan view of a swim board showing my new design;

FIGURE 2 is a bottom plan view;

FIGURE 3 is a side elevational view, the opposite side thereof being substantially the same in appearance;

FIGURE 4 is a section taken along line 4—4 of FIGURE 1;

FIGURE 5 is a front elevational view;

FIGURE 6 is a section taken along line 6—6 of FIGURE 1; and

FIGURE 7 is a rear elevational view.

The characteristic features of my design for the swim board disclosed reside in the specific overall configuration thereof in combination with the underlying ribs associated therewith, as best illustrated in FIGURES 1, 2, 5 and 6.

I claim:

The ornamental design for a swim board, as shown and described.
